UNITED STATES PATENT OFFICE.

ULYSSE DAUBRESSE, OF NOVINGER, MISSOURI.

ACETYLENE-GAS GENERATOR.

1,052,134.

Specification of Letters Patent. Patented Feb. 4, 1913.

Application filed March 3, 1911. Serial No. 612,028.

To all whom it may concern:

Be it known that I, ULYSSE DAUBRESSE, a citizen of the United States, residing at Novinger, in the county of Adair and State 5 of Missouri, have invented certain new and useful Improvements in Acetylene-Gas Generators, of which the following is a specification.

My invention relates to improvements in 10 lamps, and has for its leading object the provision of an improved form of acetylene lamp particularly adapted for miners' use.

A further object of the invention is the provision of an improved water feed for 15 acetylene lamps which will insure the water descending into the carbid chamber in such manner as to thoroughly dampen all portions of said carbid instead of merely one limited portion adjacent the drip valve.

20 Another object of my invention is to provide a miner's lamp having an improved water feed and an improved burner for the gas and means for readily cleaning the said burner and for securing the burner cleaner 25 to the lamp when not in use.

Other objects and advantages of my invention will be apparent from the following description taken in connection with the drawings, and it will be understood that I 30 may make changes in construction lying within the scope of my claim without departing from the spirit of the invention.

Figure 1 represents a side elevation of my complete lamp. Fig. 2 represents a front 35 view thereof. Fig. 3 represents a plan view of the lower section of the lamp. Fig. 4 represents a vertical sectional view of the complete lamp. Fig. 5 represents a plan view of the novel burner cleaner, and, Fig. 6 represents a sectional view of the burner removed 40 with the cleaner in operative position therein.

In the drawings, the numeral 1 designates the cylindrical casing of my lamp, having the 45 slightly rounded cover portion 2 soldered to the upper end, said cover section having the flange 3 rising from the middle portion thereof around the filling opening 4, while hinged to the bracket 4' adjacent said flange 50 is the supplemental cover section 5 having a depending flange 6 fitting in and making tight engagement with the flange 3 to retain the cover 5 in closed position.

Secured in the casing 1 intermediate the 55 length thereof is the partition 7 which divides the casing into the compartments 8.

and 9 entirely isolated from each other. Formed in the partition is an opening 10 having depending therebelow the tube 11 which projects into the compartment 9, 60 while projecting through the cover 2 is the rod 12 which passes through the compartment 8 and tube 11 and bears on its lower end the valve 13 adapted to seat against the lower end of the tube to close the passage 65 from the compartment 8 to the compartment 9. An internally threaded tube 14 surrounds the upper end of the rod 12 and an externally threaded sleeve 15 engages the threads of the tube, said sleeve having the 70 head 16 with a slot 17 formed in one side in which the laterally bent end 18 of the rod 12 is normally contained. The operation of this valve will be readily understood and it will be seen that when the compartment 8 is 75 filled with water and the sleeve 15 is screwed upward to force the rod upward and hold the valve against its seat no water can pass down through the tube 11 into the lower portion of the casing, while as the sleeve is 80 screwed down the valve will move away from its seat to allow a greater or less amount of water to pass into the compartment 9. When it is desired to quickly shut off the amount of water passing through the 85 tube or to entirely check said flow of water, I raise the bent end 18 of the rod out of the slot and partially turn the rod to cause said end to rest on the top of the head, whereby the rod will be held in elevated position to 90 seat the valve.

A flaring base flange 19 is secured to the lower end of the casing 1, said flange extending a short distance inward and having rising therefrom the interiorly threaded 95 sleeve or ring 20 providing a space 21 between said sleeve and the inner face of the casing. Engaged by said threaded sleeve is the threaded neck 22 of the carbide receptacle 23 which forms the bottom of the lamp, 100 there being a groove 24 formed at the base of said neck 22 to receive the ring or washer 25 adapted to bear against the flange 19 to make a tight joint and prevent leakage of 105 gas or water.

In the use of my lamp, I fill the compartment 8 with water and set the valve to secure the correct flow of water into the chamber 9, while filling the space 21 is the asbestos packing 26 projecting above the 110 ring 20, the water from the valve dripping onto said packing and running around

thereon as a wick. The neck 22 of the carbide receptacle has a reduced plain portion 27 projecting upward beyond the wick 26, a plurality of openings 28 being formed in the portion 27 to allow the water from the wick to seep down through the openings into the carbide receptacle. To form a closure for the top of said receptacle through which the gas can pass I mount in the portion 27 above the openings 28 the felt pad 29, a plate 30 being secured to the pad and extending across the neck and having an inverted V-shaped portion 31 at each end hooking over the portion 27, a handle 32 being secured to the plate 30 to raise and lower it and its attached pad.

To receive the gas generated in the carbide chamber I mount on the partition the T-shaped tube having the head 33 with one 20 end open and projecting through the partition just above the portion 27 of the neck of the carbide chamber while the upper end of said head is closed to prevent the water from entering the tube. Lying along the 25 partition in the chamber 8 and making water tight joint with the head is the burner tube 34 having its free end projecting from the casing 1. A wick member 35 preferably of raw wool is secured in the head tube 33 and depending into the chamber 9, while inserted in the outer end of the tube 34 is the smaller end of the lead burner 36 having the central opening 37 and having the ferrule 38 on its outer end, said burner tip 35 being forced into the tube until the tube cuts into the lead when a gas-tight joint will be formed.

From the foregoing description taken in connection with the drawings the construction of my improved lamp will be readily understood and it will be seen that when the carbide and water chambers are filled the opening of the valve 13 will permit the water to drip down upon the asbestos wick 35 member, whence it will seep through the openings in the neck of the carbide chamber into said chamber to combine with the carbide and produce a combustible gas. Said gas then passes up through the felt pad, the 45 wick 35 and the L-shaped passage formed by the tubes and then out through the opening in the burner tip.

Formed on the burner tube is the abutment shoulder 39, and to increase the brilliancy of the light given by the lamp and focus the same I mount on the end of the burner tube the curved reflector 40 having its longitudinal diameter of greater length than its lateral dimension and having the 55 sockets 41 formed at each end, the shoulder on the tube limiting the rearward movement

of the reflector. To secure the reflector in position and to at the same time facilitate the removal thereof when desired, I secure to the front of the casing 1 the spring latch member 42, the reflector being mounted on the tube with its shorter diameter parallel to the axis of the casing and then rotate the reflector a quarter turn, the rotation of the reflector bringing its wider portion against the latch member which is forced outward, the end of the reflector being engaged under the latch which fits into the socket 41 at the lower end to secure the reflector in position. Mounted on the burner tube at the rear of the reflector is the circular plate 43 having a central opening 44 to receive the burner tube and having a recess or slot formed in one side of slightly greater width than the diameter of the wider end of the burner 36, 80 a pin or steel wire member 45 being secured to the plate 43 and projecting therefrom centrally of and bisecting the slot therein. In use, when the burner becomes clogged and refuses to burn well, I remove the reflector and then slide off the plate and engage the burner tip in the slot in the plate, the pin 45 passing into the bore of the tip and serving to clear out the obstruction. It will thus be seen that the reflector and its 85 latch serve a double function in that they act not only as a reflector and lock therefor but serve to retain the cleaner in position when not in use while permitting of the ready removal thereof when desired. It is 90 also apparent that I have provided a simple, durable and efficient lamp which when employed for miners' use may be equipped with the hat hook 46 which will fulfil all the objects of the invention in a most satisfactory manner.

I claim:

A lamp of the class described, comprising a base for containing carbide, a threaded sleeve rising therefrom, a water containing 105 casing engaging the sleeve, means for admitting water from the casing to the base, a burner carried by the casing, a plate having hooks formed upon its ends for frictionally engaging the upper edge of the 110 sleeve, a handle passing through the plate, a felt pad arranged in the sleeve and held against displacement by the handle, said pad serving to filter the gas passing from the base to the burner.

In testimony whereof I affix my signature, in the presence of two witnesses,

ULYSSE DAUBRESSE.
